UNITED STATES PATENT OFFICE.

EDWARD L. TORSCH AND JAMES R. LEE, OF BALTIMORE, MARYLAND.

DESIGN FOR A BADGE-PIN.

SPECIFICATION forming part of Design No. 17,024, dated December 14, 1886.

Application filed October 15, 1886. Serial No. 216,371. Term of patent 7 years.

To all whom it may concern:

Be it known that we, EDWARD L. TORSCH and JAMES R. LEE, of Baltimore, in the State of Maryland, have invented a new and original Design for Badge-Pins, of which the following is a full, clear, and exact description.

Reference is to be had to the accompanying drawing, forming a part of this specification, in which the figure is a front view of our newly-designed badge-pin.

The leading feature of our design consists of a plate with a central elevated crown rising from the upper edge of the plate.

Another leading feature consists of the formation of the ends of the plate, also in a spaced parallel bar at the lower edge of the plate, and in a circle and triangle shown upon the face of the plate, also in a clouded or roughened surface of the plate within a plain polished border.

A represents the central or main portion of the badge-pin, which has a clouded or roughened appearance, and this portion of the badge-pin is essentially rectangular in outline. At its upper edge is shown a crown, B, of meniscus shape, and ornamented with dots *a* and diamond-shaped pendants *a'*. The ends of the badge-pin are correspondingly notched to form two angles, *c c*, and the inclines *d*, which form points *d'* at the lower corners of the badge-pin. At the lower edge of the pin is shown the bar C, which is parallel with the lower edge of the badge-pin and set off therefrom to show the narrow space *e*. A raised border, D, is shown at the edges of the badge-pin, which border is plain, except the small

dots *f* which appear upon it. Immediately below the crown B appear upon the rough surface the circle E and triangle F within the circle, the points of which touch the circle, as 40 shown.

We claim—

1. In a design for a badge-pin, a rectangular body, A, having a meniscus-shaped crown, B, at the central part of its upper edge, as 45 shown and described.

2. In a design for a badge-pin, a rectangular body, A, having its ends notched at *c c* and inclined at *d* to form points *d'*, the crown B, and a raised border, D, as shown and de- 50 scribed.

3. In a design for a badge-pin, a rectangular body, A, having a meniscus-shaped crown, B, a border, D, and the bar C below and parallel with the lower edge of the body, a space, 55 *e*, being formed between said lower edge and bar, as shown and described.

4. In a design for a badge-pin, the body A, having a roughened surface, notched and pointed ends, as at *c d d'*, a crown, B, and a 60 raised border, D, having small dots *f*, substantially as set forth.

5. In a design for a badge-pin, a rectangular body showing a roughened surface, the smooth border D, crown B, circle E, and triangle F, substantially as shown. 65

EDWARD L. TORSCH.
JAMES R. LEE.
